Attorney

UNITED STATES PATENT OFFICE.

FRANK L. UPDIKE, OF SAPULPA, OKLAHOMA.

PAPER-DISPENSING DEVICE.

1,226,928.

Specification of Letters Patent. Patented May 22, 1917.

Application filed February 17, 1916. Serial No. 78,944.

To all whom it may concern:

Be it known that I, FRANK L. UPDIKE, a citizen of the United States, residing at Sapulpa, in the county of Creek and State 5 of Oklahoma, have invented certain new and useful Improvements in Paper-Dispensing Devices, of which the following is a specification.

This invention relates to paper dispensing devices and more particularly to new 10 and useful improvements in advertising bill poster applying devices.

An object of my invention is to provide a simple, cheap and effective dispensing 15 container for use in applying advertising bill paper and the like to plain surfaces, such as bill-boards and the like.

Another object of my invention is to provide a container of the class described having 20 means for retaining a roll of blank paper, said container having means for severing the paper to form sheets.

A further object of my invention is to provide an improved closure for the container 25 whereby to prevent dislodgment of the roll of paper and at the same time permitting easy access to the interior of said container.

Other objects and advantages to be derived 30 from my invention will be apparent from the following detail description, taken with an inspection of the accompanying drawings in which,

Figure 1 is a side elevation of a dispensing 35 container embodying the improvements of my invention.

Fig. 2 is a vertical sectional view taken on line 2—2 of Fig. 1.

Fig. 3 is a transverse sectional view taken 40 on line 3—3 of Fig. 1 looking in the direction of the arrow, and

Fig. 4 is a fragmentary perspective view of a fence and my invention showing the latter in use.

Referring more particularly to the drawings, wherein similar characters of reference 45 designate like and corresponding parts throughout the various views, 1 designates my improved dispensing container in its entirety, said container preferably being cylindrical and having a bottom 2 and a peripheral side wall 3. The upper end of the container is preferably open, a closure 4 being receivable thereon. The closure 50 4 is provided with a flange 5 which embraces the upper end of the container 1,

said flange having a plurality of bayonet slots 6 engageable with a suitable pin 7 carried by the peripheral wall 3 of the container 1.

The peripheral wall 3 of the container is provided with a slot 8 extending through its length, said wall being provided with a curved blade 9 provided with cutting teeth 10 along its free margin. The flange 65 5 of the closure 4 is provided with a recess 11 registrable with the slot 8 when the closure is applied to the container, as best shown in Fig. 1.

I provide means within the container for 70 supporting a roll of paper, said means including preferably a staff 12 extending axially of the container throughout its length and provided on its lower extremity with an annular enlargement 13 and a flared recessed 75 portion 14 adapted to receive a handle 15. The staff 12 extends through the closure 4 as indicated at 16 to prevent lateral rocking movement of the container on said staff. A tube 17 is carried by the staff 12 and the roll of paper 18 is wound thereabout. The paper roll is placed within the container in such position that the free end 19 thereof is brought out over the blade 80 9 as best shown in Fig. 3.

In use the roll of paper is placed within the container 1, the free end of said roll being brought out through the slot 8 as hereinbefore explained. The container is supported by the handle 15 adjacent to a 90 bill-board 20 or the like and the paper end 19 is secured to the board by means of the usual adhesive material or paste commonly used for this purpose. The container may now be moved along the board until the full length of the particular advertising matter is exposed and by holding the paste brush against the paper 19 the teeth 10 may be employed for severing the paper. Each workman may be supplied with a roll 100 of the blank paper the same being applied at the various points on this route.

From the above description taken in connection with the accompanying drawings it is thought that a clear and comprehensive 105 understanding of the construction, use and advantages of my invention may be readily gathered, and while I have shown and described the same as embodying a specific structure I do not desire to be limited to 110 such structure but reserve the right to make such changes in said structure as do not

depart from the spirit and scope of the invention as claimed.

I claim—

In a device of the class described, the combination of a cylindrical container having one end thereof open, the opposite end being closed, the peripheral wall of said container having an elongated slot therein, a closure for the open end of the cylinder having a slot therein registering with first said slot, said closures having openings con-

centrically thereof, a tube member adapted to receive a roll of paper thereon rotatably mounted in said openings, the paper being adapted to be withdrawn through said slots, 15 a staff member extending axially of the tube throughout its length, and an enlargement formed on said staff providing supporting means for the cylinder.

In testimony whereof I affix my signature. 20

FRANK L. UPDIKE.
